Patented Apr. 11, 1922.

Inventor:

William David Taylor

UNITED STATES PATENT OFFICE.

WILLIAM DAVID TAYLOR, OF BESSEMER, ALABAMA.

SIGN.

1,412,147.

Specification of Letters Patent. Patented Apr. 11, 1922.

Application filed July 11, 1921. Serial No. 483,954.

To all whom it may concern:

Be it known that I, WILLIAM DAVID TAYLOR, a citizen of the United States of America, residing at #1728 Fifth Avenue, 5 in the city of Bessemer, county of Jefferson, State of Alabama, have invented a new and useful Sign.

This sign being made of solid iron, is permanent, from the fact that the letters for 10 the advertising will be cast in the iron and the weight and stability is sufficient to resist ordinary abuse that signs are subject to.

My invention is a life size cast iron figure to represent a man.

15 Figure 1 is a front elevation of the sign embodying my invention, and Figure 2 is a side elevation thereof.

The sign is constructed of melted iron cast in a mould, in sand, in two parts, and fastened together with bolts as shown in the 20 accompanying drawing, (side view figure).

The face, feet and hat are cast full, a small offset is used to represent the coat, the base is made of concrete, in which the sign is set up before the concrete hardens, the heels 25 of the feet are of sufficient length to secure same in the base. The fronts of the sign are life size, as shown by the front view figure in the accompanying drawing; the advertisement will be placed in the sign by 30 raised letters moulded in the iron when cast.

I claim,

A sign of the class described forming a life size, two faced human figure made of cast metal and composed of two parts, each 35 part having one side flat and the other side of the contour of a human figure, the two parts placed back to back and fastened together by bolts passing through both parts, and raised letters on the front of 40 each part.

WILLIAM DAVID TAYLOR.
